UNITED STATES PATENT OFFICE.

EUGÈNE CHAUDOIR, OF LIVERPOOL, ENGLAND.

APPARATUS FOR OPERATING AND INTERLOCKING THE LANDING AND CAGE GATES OF ELEVATORS.

1,326,440.

Specification of Letters Patent. Patented Dec. 30, 1919.

Application filed July 10, 1916, Serial No. 103,501. Renewed May 26, 1919. Serial No. 299,892.

To all whom it may concern:

Be it known that I, EUGÈNE CHAUDOIR, a subject of the King of Belgium, and residing at Wavertree, Liverpool, in the county 5 of Lancaster, England, have invented certain new and useful Improvements in Apparatus for Operating and Interlocking the Landing and Cage Gates of Elevators, operated by the instrumentality of the door 10 or gate on the lift car or cage itself, of which the following is a specification.

This invention relates to means for operating and locking the gate of a lift cage and the landing gates of the lift well, and 15 has reference more particularly to those arrangements according to which the car gate and the respective landing gate opposite the car gate, when the car is at a landing, are connected together so that movement of the 20 car gate opens the landing gate.

According to the present invention the means by which the two gates are connected together, when they are in alinement, are so articulated to, and are so adapted to co- 25 operate with the locking means, that when one of the gates is operated the unlocking is effected and both gates thereupon opened by the movement of one of them; the arrangement is, however, such that the locking 30 means are not operated merely by the alinement of the gates as the car passes the landing gates, although such alinement is a condition precedent to the operation of the locking means by the opening of one of 35 the gates.

The invention is illustrated in the accompanying drawings, in which Figures 1, 2 and 3 show the invention applied to a case in which the landing gate only is locked, and 40 in which it is released and operated by the operation of the car gate; Fig. 1 is an elevation on the line I, I, of Fig. 2, which is a corresponding side elevation in section on the line II, II, of Fig. 1; Fig. 3 is a plan in section on the line III, III, of Fig. 1; and 45 Fig. 4 is a detail of the latch and rack; Fig. 4^A is a plan with the two parts separated.

Figs. 5, 6 and 7 show the invention applied to a case in which both doors can be operated simultaneously by the operation of either the landing door from the landing side or the car door from the car; Fig. 5 is an elevation in section on the line V, V,

of Fig. 6; Fig. 6 is a side elevation in section on line VI, VI, and Fig. 7 a part plan in section on the line VII, VII, of Fig. 5.

Fig. 8 is an elevation on the line VIII, VIII, of Fig. 8^A of a modification in which the cams are on the car gate and the locking device on the landing gate; Fig. 8^A is a part plan, and Fig. 8^B shows the modification when the car gate is a collapsing gate of the Bostwick type. Figs. 9 and 10 illustrate a modification in which the car gate, 65 as well as the landing gate, is locked, Fig. 9 being an elevation in section on the line IX, IX, of Fig. 10, which is a corresponding side view in section on the line X, X, of Fig. 9. Fig. 11 is an elevation of two 70 coupled gates and an interlocking switch.

Referring first to Figs. 1, 2 and 3, a pair of cams B, B', are provided for each landing gate Z; these cams are carried from a bracket D which in turn is secured to the 75 door Z in any convenient manner, say by being attached to the bearer plates I by which the gate is carried from the track wheels H; the cams preferably have tapering or curved ends or are of doubled inclined plane form, and are located opposite each other so that they leave a vertical path between them with a bell mouthed portion at each end so as to permit the passage between the cams of a striker or roller 85 C which is affixed to the gate Y of the cage. The bracket D carries two pins P on which the cams B and B' have limited sliding movement; the movement of B is only sufficient to allow of lateral movement of 90 the striker pins C as the car sways in rising or falling, the movement of B' is, however, for a reason to be explained, considerably greater than that of B. The cam plates are connected together by springs E which 95 give the necessary elastic or lateral movement and which act as buffers to absorb the shock of the door when opening or closing. Pivoted to the same bracket D is a 100 hook, or catch F, the tail X of which is located between the cams B, B', or it may be attached to B', the attachment being such that while the cams are in their normal position (that shown in full lines Fig. 1), the beak or hook f¹ of the latch engages with a fixed pin or one of a series of pins or one of the teeth g¹ of the rack G, which latter is secured to the gate frame, gate carrier,

or wall, in any convenient manner. Another suitable form of latch and rack is shown in elevation and plan in Figs. 4 and 4^A.

The object of fitting a plurality of pins or teeth g^1 is that while normally the latch engages with the tooth most remote from the cams when the gate is effectually closed, it will, if the gate should not be quite closed, engage with one of the nearer pins or teeth, 10 thus effectually locking the gate. The same result may of course be obtained by means of a single pin or tooth and by providing the latch with a plurality of engaging teeth, as shown, for instance, in the latch illustrated in Fig. 8^B. The latch may be pivoted to the fixed bracket D as in the arrangement of Figs. 1 to 3, or, as shown in full lines in Fig. 8^B, it may be pivoted to the gate at some distance from the cam and be 20 connected by a rod such as Q to an actuating lever pivoted on the bracket D; in the case of a collapsing gate, the rod Q, instead of being of rigid construction, would be jointed as shown in the chain dotted lines 25 of Fig. 8^B so as to allow for the approach of the pickets as the gate is collapsed, and a spring such as g^1 would be fitted.

The path or space left between the cams B, B', permits of the free passage up or 30 down of the striker or pin C while the car is moving and during the time that the car gate Y is closed; there is therefore no movement of the locking mechanism during the travel or during the starting up or stopping 35 of the car.

When the car is brought to rest in proper position in relation to a landing, the striker or pin C comes to rest between the two cams B and B'; if now the car gate be opened, the 40 striker C comes into contact with the cam B' which is moved in opposition to the springs E until it reaches its limit of movement on the pins P. This limited movement permits the tail X of the latch F to follow 45 the cam B', whereupon the latch becomes disengaged from the rack G, thus unlocking the landing gate.

Further movement of the striker C consequent upon the opening of the car gate 50 is effective, through the cam B', pins P and bracket D, in opening the landing gate; when the car gate is closed the striker C comes into contact with the cam plate B, and the cam plate B', being now released 55 from the pressure of C, is drawn toward B by the springs E, so that while the car gate in closing is effective in closing the landing gate, this act also leaves the latch F free to engage with the rack G so as to lock 60 the gate as soon as the closing is accomplished; thus the opening movement of the car gate, by, say, the lift attendant, unlocks the landing gate and opens it, while the closing movement of this gate closes the 65 landing gate and locks it.

The lift actuating means is interlocked in any suitable manner with the car gate so that the lift cannot be operated while the car gate is open. Any suitable device may be employed for this purpose; for instance, in the case of electrically operated lifts, a switch such as is shown diagrammatically in Fig. 1 may be employed; the lever A² is pivoted at a^4 and the end a^5 of the lever is shaped so as to be located, when drawn down by the spring a^6 , directly in the path of the hooked end f^1 of the latch F as the latter moves into its engaging position; when in this position the connection between the conductors a^7 and a^8 connected 70 respectively to the switch A² and the contact piece a^9 , is broken and as these conductors connect the switch in control circuit of the motor, the latter cannot be started until the hooked end f^1 of the latch F is 75 engaged with one of the teeth of the detent G. Any of the well known types of gate-operated, or latch operated switches may be employed provided they insure that, when the gate is open the motor driving the lift is rendered inoperative. For example a switch such as A, Fig. 11, is operated by the gate in such manner that the switch is opened concurrently with the gate; this switch is inserted in the main or a control 80 circuit so that when it is open the lift can not be operated; in the example illustrated in Fig. 11, the cam or roller a^1 is carried from the car gate, and when the gate is closed this roller supports the switch lever 85 90 a^2 so that the switch bridges the contacts a^3 and closes the circuit; when the gate is opened the support is withdrawn from the lever and the circuit is opened. Any suitable type of switch may be used and it may 95 be operated in any suitable way by the gate; for instance, where the gate has a locking latch the switch may be so operated that the circuit remains open until the latch is 100 actuated to lock the gate. 105 110

In the example illustrated the car gate and the landing gates are ordinary sliding gates supported by bearers I₁ from the track wheels H₁ which run on the tracks H', these tracks being carried, in the case of the landing gates, from the wall or gate frame, and in the case of the car, from the car body Y'. 115

If desired, the car gate may be locked by a catch similar to F; this arrangement is shown in Figs. 9 and 10. In these figures the cams B and B', the bracket D, the latch F and the catch G are constructed and connected as already described in connection with Figs. 1, 2 and 3, and these parts are located on the landing door or its frame, as 120 described. The latch F² is carried on a pivot f^{15} fixed to the cage gate, and is adapted 125 to engage with the catch pin g^2 fixed to the cage frame; the latch F² is operated by means of a lever f^2 pivoted at f^3 to the cage 130

gate, and provided with two pins f^4 and f^5 , and with a striker piece C^2 which takes the place of the pin C of Figs. 1 to 3, and which comes to rest, when the car stops at a landing, between the cams B , B' ; the movement of the lever is limited by the pins c^2 and c^3 ; when there is relative movement between C^2 and the cams B , B' , caused say, by opening the cage gate, or by opening the landing gate the lever f^2 tilts and one of the two pins f^4 or f^5 raises the latch F^2 so that it may clear the pin g^2 ; the pin g^2 is so located that limited movement of the car gate is permitted before disengagement. Further opening movement of the car gate moves B' relatively to the bracket D on which the latch F of the landing gate is pivoted. This releases the tail X of the latch F and frees the landing gate to move with the car gate. In other respects the action is similar to that described in connection with Figs. 1 to 3, the lever f^2 , as the gate is closed, coming into contact with the stop c^3 on the car gate and moving the landing gate by contact with the cam B .

In the figures just described Y^4 is the cage gate and Z^4 the landing gate.

In some cases, in say, push button lifts, it is necessary that the landing gates and the car gate shall be opened, when the car is opposite the appropriate landing, by an intending passenger in the act of opening the landing gate on that landing, and also that both gates shall be capable of being operated by the car gate when the car is opposite the landing at which the passenger desires to leave the car.

In such cases the lock on the cage gate, where it is desired to lock this gate, is constructed as described in connection with Figs. 9 and 10, and it will be seen that with this construction the latch F^2 is released when the landing gate is opened and the striker piece C^2 engages with the cam B , or when the cage gate is opened and the striker piece engages with B' ; in each case the tilting of f^2 raises F^2 .

The arrangement of the cams and latch for a landing gate of a push button lift is shown in Figs. 5, 6 and 7. In this case Y^3 is the cage gate, and Z^3 the landing gate fitted with runners H^4 carried from plates I^3 and rolling on tracks H^5 ; the cage gate is omitted from Fig. 5. The cams B^2 and B^3 are slidably carried on the pins S^1 secured to the gate Z^3 by the bracket D^3 ; springs S^2 are interposed between the cam B^2 and the bracket D^3 which normally maintains this cam in its extreme position on the left of the bracket D^3 and against the stops s^1 ; and springs S^3 are interposed between collars s^2 on the other ends of the pins, which springs maintain the cam B^3 in its extreme position to the left, and in contact with the bosses d^1 of the bracket D^3 . The latch F^3

is pivoted at f^8 to the bracket D^3 and its hooked end is adapted to engage with the teeth of the detent G^3 ; the tail f^9 of the catch is provided with an engaging piece X^3 , located between the cams B^2 and B^3 , and the catch is normally maintained by the cam B^3 in engaging position; the cam B^2 is articulated by the rod T , the lever t^1 , the rod t^2 , and the lever t^3 , or by any other suitable connection, to the gate operating handle W . A striker piece C^3 is attached to the cage gate Y^3 and this piece, as shown in chain-dotted lines Fig. 5, comes into interposing position between the cams B^2 and B^3 when the cage gate is in alinement with the landing gate. A^3 is a switch in a circuit which controls the motive power which operates the lift.

The action is as follows:—A passenger on a landing desiring to enter the cage when the latter has come to rest in alinement with the landing door, operates the handle W in the direction of the arrow; this moves the cam B^2 to the right in opposition to the springs S^2 ; when the striker piece C^3 is in interposing position (but not otherwise) the movement of the cam B^2 is transmitted to the cam B^3 and as the latter moves to the right the engaging piece X^3 is released from engagement with the cam B^3 , and the catch F^3 is released from the detent G^3 ; further movement of the handle W to the right opens both gates, the cage gate Y^3 being opened by engagement between the cam B^2 and the striker piece C^3 . After the passenger has entered the cage, the closing of the cage gate closes the landing gate and locks it, and the lift cannot be operated till this is done and the switch A^3 is closed. On arrival at the desired landing, the striker piece C^3 will be located between the cams on the gate of that landing, and the opening of the car gate will result in the unlocking and opening of the landing gate.

Where it is desired with this arrangement to lock the car gate so that it can be opened only when the car is opposite a landing, the car gate locking arrangement described in relation to Figs. 9 and 10 is, as stated, fitted, in which case the striker C^2 on the tail of the lever f^2 which operates the car gate locking latch F^2 , takes the place of the striker C^3 in the arrangement just described.

It will be seen that when the double lock is fitted, the latch F^2 is released by the operation of the cams when the landing gate is opened, and that it is also released when the car gate is opened, by the limited movement permitted to the car gate before it begins to unlock and open the landing gate. It will be further seen that in each case the co-operation of the striker tail piece C^2 or equivalent device is required before any landing gate can be opened, and that this co-operation is only afforded when the car

is at rest in its proper position in relation to a landing.

The arrangement is equally applicable to those cases in which the car gate or the 5 landing gate is made in the form of a double gate, say Z' , Z^2 , as shown in Fig. 11. In this case each half of the gate is provided with a rack J , which racks are coupled together by a pinion O mounted on ball bearings so 10 as to insure sympathetic movement of the parts Z' and Z^2 in opening and closing.

The track wheels H^2 are preferably mounted on ball or roller bearings comprising a race L and balls or rollers K , and in 15 the arrangement described, the ball bearing spindle M is carried in slots in the bearers I^2 of the gates Z' , Z^2 so as to permit a relative limited movement between the spindles and the gates, to ease the shock in opening 20 or closing, should the track wheels H^2 meet with an obstruction.

Instead of fixing the cams B , B' to the landing gates as described in Figs. 1 to 4, these may of course be fixed to the car gate 25 Y^4 , as shown in Figs. 8 and 8^A, in which case the latch F^4 would be fixed on the landing gate Z^4 , the tail part X^4 of the latch coming between the cams B^4 and B^5 when the car is in proper position in respect to the 30 landing.

It follows from the description given that the cage gate cannot be closed by an attendant or a passenger in the cage without closing the landing gate at the same time; if, 35 therefore, a device be fitted to the cage door, which when the latter is open is effective in preventing the operation of the motive power by which the lift is operated, this device will at each landing be connected to 40 the landing gate, and will be as effective in insuring the closing of the landing gate as would be the case if each landing gate were fitted with such a device. In cases therefore where my invention is applied to lift 45 gates, only one such device on the car gate need be fitted.

Having now fully described my invention, I declare that what I claim, and desire to secure by Letters Patent is:—

50 1. In an elevator and in combination with the cage gate and the landing gate; a locking device on the cage gate; an actuating part on the cage gate movable relatively to the cage gate and adapted by such relative movement to actuate the cage gate locking device; stops to limit the said relative movement; a locking device on the landing gate; an actuating part on the landing gate having limited movement relatively to the landing 55 gate and adapted by such movement to actuate the landing gate locking device; stops to limit the said relative movement; said two actuating parts being located on the respective gates so that they come into operative relationship when the gates are in ver-

tical alinement, and, when one of the gates is moved transversely relatively to the other, said parts are by contact with each other moved to their limit positions, and each thereby actuating its respective device, said 70 parts after the said movement has reached its limit serving to connect the two gates together; substantially as described.

2. In an elevator and in combination with the cage gate and the landing gate; a locking device on the cage gate; a lever pivoted to the cage gate and adapted in its limiting positions to open the locking device; stops limiting the movement of said lever; a locking lever on the landing gate; a tail piece on 75 said locking lever; a striker pin, a pair of cams on the landing gate between which the striker pin passes as the cage moves up and down and one of which has limited movement relatively to the landing gate and in 80 one of its limiting positions engages the tail piece so as to close the landing gate locking lever and springs tending to move the said cam into the engaging position; substantially 85 as described.

3. In combination with the cage gate and the landing gate of an elevator; a locking device on the one gate; a lever having limited angular movement and adapted to 90 actuate the locking device; a striker pin carried 95 from said lever, a pair of cam surfaces on the other gate, one of the said surfaces being spring controlled and having limited lateral movement relatively to the gate; a locking device on this gate; a lever pivoted 100 on the gate actuating the locking device; a tail piece carried by said lever which tail piece is normally pressed by the last mentioned cam plate to cause the engagement 105 of the locking device, said striker pin lying between the cam plates when the gates are in alinement and when the gate to which it is attached is moved, being first deflected by contact with the cam plates so as to release the locking device connected with it 110 and then to move the said cam plate relatively to the second gate and permit the movement of the tail piece necessary to disengage the locking device connected to it; substantially as described.

4. In combination with the cage gate and the landing gate of an elevator; a striker pin carried on the cage gate; a pair of cams carried on the landing gate, said cams being spring controlled and each having limited relative movement to the gate; an operating handle on the landing gate; means articulating one of the said cam plates to said handle; a locking device; a lever pivoted to the landing gate and having a tail 120 piece normally making contact with the other cam plate which contact maintains the locking device in the engaging position; the striker pin on the cage gate forming an 125 interposing piece between the cams by which 130

movement transmitted to the handle - controlled-cam is transmitted to the other cam to release the locking device, said striker pin and cams also serving to couple the gates together so that they open and close in unison; substantially as described.

5. In combination with the cage gate and the landing gate of an elevator; a striker pin; a lever carrying the striker pin and having limited angular movement; a locking device on the cage gate actuated by the said lever; a pair of cams carried on the landing gate, said cams being spring controlled and each having limited movement 10 relatively to the gate; an operating handle on the landing gate; means articulating one of said cam plates to said handle; a locking device; a lever pivoted to the landing

gate and having a tail piece normally making contact with the other cam plate which contact maintains the locking device in the engaging position; the striker pin on the cage gate forming an interposing piece between the cams by which movement transmitted to the handle controlled cam is transmitted to the other cam to release the locking device, said striker pin and cams also serving to couple the gates together so that they open and close in unison; substantially as described.

15 In witness whereof I have hereunto set my hand in presence of two witnesses.

EUGÈNE CHAUDOIR.
